UNITED STATES PATENT OFFICE.

WALTER C. WHITE, OF PITTSBURGH, PENNSYLVANIA.

TRAIN-PIPE COUPLING.

1,321,689.

Specification of Letters Patent. Patented Nov. 11, 1919.

Application filed October 11, 1916. Serial No. 125,040.

To all whom it may concern:

Be it known that I, WALTER C. WHITE, a well-known manner and I have illustrated citizen of the United States, residing at transverse plates 80 inserted through the Pittsburgh, in the county of Allegheny and yoke and having their ends resting upon the State of Pennsylvania, have invented certain hangers 53, a spring 81 being disposed with 60 tain new and useful Improvements in in the yoke between said plates so that the Train-Pipe Couplings, of which the following yoke will be yieldably supported, but the ing is a specification.

This invention relates to train pipe coupling or draw head will be transmitted to 10 plings and has special reference to means the spring and thence through the front 65 for supporting the train pipes and the train plate 80 and the hangers to the car body, pipe coupler head, the object being to permit The train pipe coupler head 1 is suspended mit the train pipes to accommodate them below the car coupler head 49 by a shelf 55 selves to the shifting positions of the car which projects forwardly from the lower 15 couplings in rounding curves while a train ends of the guide rods 50, the upper ends 70 is in motion or in the act of coupling or un-coupling of said rods being secured to a brace 51 75 coupling cars or from any other cause shift which extends longitudinally of the draw ing laterally. The invention also seeks to head 49 and is rigidly secured to the bottom provide means whereby the train pipe coupler of the same by straps or similar clamping 20 pling heads will be maintained in close contact devices 52. The rear end of the brace 51 75 contact so that the joints will not leak notwithstanding the front end of the draft yoke standing the lost motion or play in the car 54 and is formed on an arc so that it may 25 couplings. The invention also seeks to pro- rock upon the front end of the yoke as the vide means for suspending the train pipes draw head moves laterally from time to 30 and the train pipe coupling head in such a time. The shelf 55 is further supported by 80 manner that assembling of the parts will be side braces 56 which extend upward from 35 facilitated. the rear portion of the shelf and are se- 85

In the accompanying drawings: secured to the brace 51 and to the straps or Figure 1 is a side elevation of a car coupling clamps 52, as shown and as will be readily 30 pling and of my improved train pipe coupler understood. The train pipe coupler head 1 85 coupling suspended therefrom;

Fig. 2 is a bottom plan view of the car arms 8 which are slotted, as shown at 9 in coupling with parts of the suspending device Fig. 3, so as to engage over pins upon a pipe vices in horizontal section;

Figs. 3 and 3^a are bottom plan views of engage and fit between the guide rods 50, as 90 the train pipes and their mountings, indicated will be readily understood on reference to ing in dotted lines the manner in which Fig. 4. The coupler head 1 is provided with they are permitted to shift so as to respond longitudinal chambers which receive the front to the movements of the car coupling; ends of the train pipes 5, 6 and 7 and these 40

Fig. 4 is an inverted enlarged horizontal train pipes are constructed of metal and 95 section taken centrally through the train to carry the air for operating the brakes, steam pipe coupling head;

Fig. 5 is a view showing, in elevation and a suitable agent for operating the train section, the abutment plates by which the signals. The signals may be operated by 45 rear portions of the train pipes are superimposed compressed air or may be operated by elec- 100 ported;

Fig. 6 is a detail perspective view showing an electrical cable or conductor for current ing a different form of the rear abutment to operate the signals. The lowest pipe, plate.

50 In the drawings, the reference numeral provided with a drain cock to permit the 105 49 designates the car coupling or draw head escape of the water of condensation, as in which is pivotally attached at its rear end indicated conventionally at 100.

to a draft yoke 54 which is slidably sup- The coupler head is constructed in its ported upon hangers 53 which are secured front wall with ports 12 in which are seated 55 rigidly to and depend from the car body, gaskets 13 which are constructed with 110

flanges 15 over which retainers 14, secured upon the front wall 11, project so as to hold the gaskets in place. When the coupler heads come together, the gaskets are compressed and will form fluid-tight joints so that no air or steam may leak out and be wasted and the coupling will be operative at all times. The coupler head is provided at its front end on one side with laterally extending plates or wings 32 between which a guiding arm or tongue 27 on an opposed coupler head passes, the said tongue being tapered to present a point 28 which will enter between the wings of the opposed head even though there be great variation in the height of the cars to which the respective heads are attached and the engagement of the guiding arm or tongue with the said wings will effect the vertical movement necessary to bring the ports into perfect register. In order to further guide the coupler heads into proper register, the inner surface of the guiding arm or tongue is provided with a laterally extending portion 29, from the outer end of which a longitudinal portion 30 extends forward and from the forward terminal of this longitudinal portion an obliquely disposed portion 31 extends. The outer side of this coupler head is provided with an obliquely disposed portion 22 at its forward extremity which is disposed at a slightly different angle from that given the surface 29 and from the outer edge of the said surface 22 an obliquely disposed portion 23 extends adapted to ride upon the surface 31 of the opposed coupler so that the coupler heads will be directed laterally and the desired alignment of the ports and the binding of the heads effected. By disposing the surface 22 at a sharper angle than the surface 29, the edge only of the outer surface 22 will bear upon the surface 29 when the heads are coupled, thus reducing the frictional resistance to free movement. Moreover, the point or extreme edge may move forward as the parts wear away so that the required engagement of the parts will be maintained. This operation is further aided by the provision of an offset 24 having a convex surface 26 upon the outer side of the coupler head immediately in rear of the surface 23, and rearwardly converging ribs 25 are provided at the upper and lower edges of the said offset to be engaged by the extremity 28 of the guiding arm. To facilitate the escape of snow and dirt that may tend to collect between the coupler heads, I provide a vertical groove 31^a, the upper and lower ends of which are open, at the junction of the front wall 11 and the surface 29.

The train pipes 5, 6 and 7 are provided with ball and socket joints 58^a which permit universal movement between the sections 65 of the train pipe so that they may remain in

the central line of the draft gearing, notwithstanding a vertical or horizontal movement of the coupler head. The front ends of the several train pipes pass through the pipe carrier 58 and enter the rear ends of the chambers in the coupler head. The rear portions of the train pipes are supported by abutment plates, hangers or brackets 37 and 60 and in rear of the rear bracket 60, the pipes are bent laterally so as to extend to the opposite sides of the car body and there connect with the usual train lines 82 which are now commonly mounted upon the car body and are equipped at their forward ends with manually operated coupling heads and valves to permit flow of the fluids through the entire length of the train. By thus connecting my train pipes with the train lines now ordinarily provided, I am enabled to couple a car equipped with my improvements in a train not so equipped, but it is to be understood that it is the intention to equip all cars with my improvements so that the train pipes will be automatically and effectually coupled without requiring operators to pass between the cars or perform any other manual work which will endanger life or limb. The forward hanger or abutment plate 37 is secured to and depends from the car coupler by means of one of the clamps 52 which secure the brace 51 thereto and for this purpose the upper end of the abutment plate is carried forwardly, as at 16, and constructed with a depending flange so that it will hang over the under portion of the said clamp and, consequently, be firmly secured to the car coupler when the said clamp is secured in place. As the clamp will fit closely between the body of the plate and the depending flange on the forwardly extending portion 16, it is evident that the abutment plate cannot slip out or be accidentally detached therefrom. The rear abutment plate 60 is constructed with a similar hook-like member 17 at its upper end which receives the under portion of a divided strap 18 which passes around the hangers 53 and below the draft yoke so as to secure the plate 60 to the said hangers in the same manner that the plate 37 is secured, the ends of the strap 18 being provided with perforated lugs which receive a clamping bolt 19, as shown most clearly in Fig. 2. The openings through the plates 37 and 60 which receive the train pipes have the vertical portions of their walls flared, as shown at 61, so that the pipes may fit loosely within the plates and, consequently, the lateral movement of the car coupler will be accommodated without any liability of the train pipes to bind in the abutment plates and be thereby bent or otherwise damaged so as to unsatisfactorily perform their allotted functions. On its rear side, at its upper end, the front abutment plate 37 is formed with an arcuate por-

tion 37^a so that it may rock on the front end of the draft yoke 54 as the draw head moves laterally from time to time.

The train lines 82, at the junctions thereof with the train pipes 5, 6 and 7 are supported loosely in hangers or brackets 62 on the bottom of the car body and are preferably slightly flexible so that they will possess more or less resiliency and, consequently, 10 may spring laterally as the car coupling and the train pipes sway during travel of the train or in the acts of coupling or uncoupling.

By reference to the dotted lines in Fig. 2, 15 it will be noted that during the travel of a train, the car coupling moves laterally to a considerable extent and that this movement causes the draft yoke 54 at times to impinge against the sides of the hangers 53. In- 20asmuch as the plate 37 is secured to the car coupling and the train pipe coupling head is suspended directly below the car coupling, it is evident that this lateral movement will be transmitted to the forward portions of 25 the train pipes and to the train pipe coupler head. The manner herein disclosed of ar- ranging and supporting the train pipes per- mits them to flex laterally so that there will be no excessive bending strain thereon, as 30 indicated by the dotted lines in Fig. 3. It will also be understood that the pulling and pushing strain upon the car couplings effects longitudinal movement thereof, one purpose of the draft spring 81 being to compensate 35 for this longitudinal shifting of the car couplings. This longitudinal shifting of the car couplings will also be transmitted to the train pipes and the train pipe coupler as indicated by dotted lines in Fig. 3. To 40 permit the train pipes to accommodate this longitudinal movement without being sub- jected to a breaking compression or pulling strain, I provide telescoping joints 59 in the train pipes immediately in advance of the 45 abutment plate 60. These telescopic joints will permit longitudinal expansion or con- traction of the train pipe so that the longi- tudinal movement of the car couplings will not be liable to cause uncoupling of the train 50 pipes or such separation of the same as will permit leakage of any of the fluids. A col- ller or shoulder 36 is provided upon the air pipe 6 in advance of the abutment plate 37 and bears against said plate so that the said 55 pipe will bear upon the said plate and fur- nish means whereby pressure may be ap- plied to the coupler head to hold the head close to the opposed coupler head. Lock nuts 20 are provided upon the train pipes at 60 the rear of the plate 37 to be turned home against a telescope sleeve to compress the packing in the telescope joints.

The construction of the telescoping joints 59 is substantially the same as that shown 65 in Fig. 4, which shows the connection of the

train pipe 6 with the coupler head. The train pipe terminates in a nozzle or tube 64 which enters the rear end of the chamber in the coupler head and has a sleeve 66 mounted thereon, the rear end of the said 70 sleeve having a threaded engagement with a nut 67 which bears against the nut 68 which secures the socket member 69 of a ball joint 58^a upon the nozzle 64. The front end of the sleeve 66 bears against a gasket 65 75 which is fitted around the nozzle 64 and en- gages the bore of the chamber in the cham- ber in the train pipe coupler head. A washer 74 is fitted around the sleeve in ad- vance of and bears against the gasket so as 80 to receive the pressure of the fluid which escapes from the nozzle and flows into the space between the end of the nozzle and the wall of the coupler head chamber. It will be readily understood that the pressure of 85 the fluid flowing through the train pipe is thus utilized to compress the gasket and form a fluid-tight joint. The construction thus far described suffices for the joints 59, it being understood that the coupler head 90 is the equivalent of the outer section or member of the joint. In applying the joint to the coupler head, a follower 70 is mounted upon the sleeve or follower 66 and has a sliding engagement therewith but is con- 95 strained against rotation about the same. The outer end of this follower 70 is engaged by a nut 71 which may rotate about the follower or sleeve 66 and bears against the nut 67 so that, when the nut 71 is rotated, 100 the follower or sleeve 70 will be moved lon- gitudinally to vary the tension of a spring 72 which is coiled about the sleeve 66 be- tween the front end of the follower 70 and the annular shoulder 73 formed in the cou- 105 pler head. The said spring, by its expansion, holds the coupler head firmly against the opposed coupler head so that, notwithstanding, the slight play which is permitted in the car coupling heads, the train pipe coupler 110 heads will form a tight joint at all times. The pressure exerted by the spring upon the follower 70 will be transmitted through the pipe to the collar 36 and will be, conse- 115 quently, exerted upon the abutment plate 37, so that the movement of the car coupling in starting or stopping the train or in the operations of coupling or uncoupling will not cause a separation of the opposing train- 120 pipe coupler heads. The relative movement between the car coupler and the draft rig- ging is accommodated in the telescoping joints 59. When the car couplings are un- 125 der pulling strain, the knuckles of the same will be slightly separated from the inner walls of the respective coupler heads. The springs 72 force the train - pipe - coupler heads together so as to maintain tight joints and prevent them separating in unison with the slight separation of the car-coupler 130

heads and the knuckles. The impact of the cars in coupling compresses the spring 72 which is then called upon to push forward the top and bottom train pipes as well as the coupling head. In performing this work, the spring pulls the pipes forward from the telescopic joints through the flared openings of the abutment plate.

- In the arrangement illustrated in Fig. 1, 10 the several train pipes pass through a solid abutment plate but it may sometimes be preferred and more convenient to employ an abutment plate 75 constructed as shown in Fig. 6. This plate is provided with a 15 hook-shaped upper portion 76, corresponding to the hook-shaped members 16 and 17, but is further constructed with a vertically disposed open ended slot receiving the carrier plates or sections 77, 78 and 79, which 20 have a tongue and groove engagement with the side walls of the slot so that they cannot fall forward or backward. The sections will have notches 84 in their meeting edges which are adapted to fit around and support 25 the train pipes and after they are moved vertically upward in the slot, they are secured in place by transverse pins 83 fitted in seats provided therefor in the walls of the slot and the edges of the lowermost plate. 30 The uppermost train line, which will generally be an electrical cable, may be carried through a notch 85 formed in the edge of the plate and held therein by a keeper 86 of any convenient form which will bridge the 35 notch and pass over the said cable.

The fluid pressure is fed into the train lines after the coupler heads are properly coupled by manipulating rods 39 attached to the stems of the cut-off valves 38 and 40 tending to the side of the car and supported preferably but not necessarily upon the car steps, indicated at 40. The rods 39 are loosely supported so that they may move freely in all directions and thereby accommodate all movement of the train pipes, as 45 shown by the dotted lines in Fig. 3. The rods will, of course, extend to both sides of the car so that the valves may be manipulated from either side and universal joints, 50 indicated at 139, are interposed in the lengths of the rods to avoid breaking of the same. As the train pipes are bowed and connected to ball joints and telescopic sleeves, the bowed portions of the pipes and 55 the cut-out valves tend to swing to one side and out of alignment as movement is caused in the pipes by the shifting of the coupler heads. I utilize the rods 39 in holding the pipes properly centered or aligned. 60 The rod is mounted in a hanger 140 which may be suspended from any part of the car body but, for reasons of accessibility, will generally be arranged on the sides of the car steps. An abutment 141 is provided on the

outer portion of the rod and a spring 142 65 is coiled around the rod between said abutment and the hanger, the spring tending to hold the pipe in the position shown in full lines in Fig. 3 and returning it to such position from either position indicated by the 70 dotted lines.

Having thus described the invention, what is claimed as new is:

1. The combination with a car coupling, draft rigging, and hanger disposed adjacent the draft rigging, of spaced abutment plates secured to and depending from the hanger and the car coupling respectively, a train pipe coupler head carried by the car coupling, and rigid train pipes connected 80 with the train pipe coupler head and passing through the said abutment plates and provided with telescopic joints disposed between the said plates.

2. In an apparatus for the purpose set 85 forth, the combination of train lines having flexible portions, means for loosely supporting said flexible portions, brackets having flared openings therethrough, and train pipes extending loosely through said flared openings and having laterally disposed portions 90 coupled to the flexible portions of the train lines.

3. In an apparatus for the purpose set 95 forth, the combination of a car coupling, a train pipe coupler head suspended from the car coupling, train pipes supported at their rear portions from the car coupler and constructed to accommodate longitudinal and lateral movement of the car coupling, one of 100 said pipes having a telescopic engagement with the train pipe coupler head, and a spring coiled around said pipe within said head and holding said head against an opposed head.

4. In an apparatus for the purpose set 105 forth, the combination of a car coupler, a pipe carrier suspended from the forward end of the car coupler, an abutment plate secured to the rear portion of the car coupler, an abutment plate secured to a fixed support in the rear of the first-mentioned abutment plate, a train pipe coupler head connected to said pipe carrier, train pipes passing through said pipe carrier and connected to the train pipe coupler head, the rear portions of said pipes being loosely supported by the said abutment plates, telescopic joints in said pipes between the said 110 abutment plates and bearing against the rear abutment plate, and a collar on one of said pipes bearing constantly against the front abutment plate.

5. In an apparatus for the purpose set 115 forth, the combination of a car coupler, draft rigging to which the car coupler is pivoted, hangers adjacent the draft rigging, a longitudinal brace fitted against the under 120

- side of the car coupler and bearing against the front end of the draft rigging and having a rocking engagement therewith, straps passed around the car coupler and the brace 5 to secure the brace to the car coupler, an abutment plate having a forwardly extending hook-shaped portion at its upper end fitting over one of the said straps, a rear abutment plate having a hook-shaped portion 10 at its upper end, a strap passing around said hook-shaped portion and the hangers, a train pipe coupler head supported from the front end of the longitudinal brace, and train pipes connected with said train pipe coupler head and extending therefrom and through said abutment plate.
6. The combination with a car coupling, draft rigging including a yoke, and hangers adjacent and supporting said yoke, of an abutment plate secured to and depending from the hangers, a train-pipe-coupler head carried by the car coupling, and train pipes connected with the train-pipe-coupler head and passing through and bearing 25 against the abutment plate.
7. The combination with a car coupling, and draft rigging, of a train-pipe-coupler head carried by the forward portion of the car coupling, an abutment plate depending from the rear portion of the car coupling adjacent the draft rigging, train pipes connected with the train-pipe-coupler head and passing through said abutment plate, and a shoulder on one of the pipes bearing 35 against the abutment plate.
8. The combination with a car coupling including a bar, and train line pipes, of a train-pipe-coupler head carried by the car coupling, a vertically movable pipe carrier 40 attached to the rear of the train-pipe-coupler head, a bracket secured to the bar in rear of said train pipe carrier and provided with laterally flared openings, and rigid train pipes connected with the train-pipe-coupler head and extending loosely through 45 said train pipe carrier and said flared openings and connecting with the train line pipes.
9. The combination of a car coupling, a pipe carrier suspended from the car coupling, an abutment plate depending from the rear end of the car coupling, a second abutment plate secured to a fixed support in rear of the first-mentioned abutment 55 plate, a train-pipe coupler head connected to said pipe carrier, train pipes passing through said pipe carrier and connected to the train-pipe-coupler head, the rear portions of said pipes being supported by the abutment plates, two of the pipes being 60 slideable through the front abutment plate, a shoulder on one of the pipes bearing against said plate, telescopic joints in the train pipes between the abutment plates and bearing against the rear abutment plate, and an expansion spring in the train pipe coupler head to move the train pipes forwardly.
10. The combination of a car coupling, a pipe carrier suspended from the car coupling, an abutment plate depending from the rear end of the car coupling, a second abutment plate secured to a fixed support in rear of the first-mentioned abutment plate, a train-pipe-coupler head connected to said pipe carrier, train pipes passing through said pipe carrier and connected to the train-pipe-coupler head, the rear portions of said pipes being supported by the abutment plates, two of the pipes being slideable through the front abutment plate, telescopic joints in the train pipes between the abutment plates and bearing against the rear abutment plate, a shoulder on one of the train pipes bearing constantly against the front abutment plate, said pipe being telescopic connected with the train-pipe-coupler head, and a spring on said pipe bearing against said head to hold said shoulder against the abutment plate and maintain a tight joint between opposed heads.
11. The combination of a car coupling, a train pipe coupler head carried by the car coupling, metallic train pipes connecting said head with the train pipe lines of a car, an abutment plate depending from the car coupling and supporting said pipes, one of the pipes having a shoulder bearing against said abutment plate, and means on said train pipe coupler head exerting pressure on said plate to hold opposed train pipe coupler heads in close contact and compensate for movement between and within opposing car couplings.
12. The combination of a car coupling, a train-pipe-coupler head suspended therefrom, metallic train pipes supported from the rear portion of the car coupling and connected to the train-pipe-coupler head, and constructed to accommodate longitudinal and lateral movement of the pipes and of the car coupling, cut-off valves in said pipes, and swinging operating rods connected to said valves and extending to and loosely held at the side of the car.
13. The combination of a car coupling, a train-pipe-coupler head suspended therefrom, train pipes supported from the rear portion of the car coupling and connected to the train-pipe-coupler head and constructed to accommodate longitudinal and lateral movement of the car coupling, cut-off valves in said pipes, a hanger on the car steps, and operating rods loosely mounted in said hanger and connected with said valves.
14. The combination of train pipes having flexible metallic portions, means for sup-

porting said flexible portions, cut-off valves in said pipes, and loosely-mounted levers arranged to move in unison with said pipes and connected with said valves.

5. 15. The combination of train pipes having flexible metallic portions, means for supporting said flexible portions, cut-off valves in said pipes, loosely-mounted levers arranged to move in unison with said pipes 10 and connected with said valves, and means acting on the operating rods to maintain the train-pipes in alinement.

16. The combination of train lines having loosely-supported flexible portions, and

train pipes having laterally disposed portions coupled to the flexible portions of the train lines. 15

17. The combination of a car coupler, draft rigging to which the car coupler is pivoted, an abutment plate depending from 20 the car coupler and having a rocking engagement with the draft rigging, a train-pipe-coupler head suspended from the car coupler, and train pipes connected with the train-pipe-coupler head and passing there- 25 from through the abutment plate.

In testimony whereof I affix my signature.
WALTER C. WHITE. [L.S.]
